PAUL WARE, OF NEW YORK, N. Y., ASSIGNOR TO WARE RADIO, INC., A CORPORATION OF DELAWARE.

TWO-WAY RADIO COMMUNICATION SYSTEM.

Application filed September 4, 1920. Serial No. 408,132.

This invention relates to system of two-way radio communication, and has for its object to provide a system of two-way or duplex radio communication which is operable in the same manner as land wire telephone and telegraph systems, without the necessity of changing the circuit adjustments for sending and receiving, or using throw-over switches, etc.

Previous systems of two-way communication have been proposed for both long and short distances, the former requiring the sending station to be at such distance from the receiving station as to prevent the receiving circuit from being paralyzed by the powerful sending circuit; and the latter consisting of a single transmitting and receiving element at each station, such as an audion, giving satisfactory communication over shorter distances.

The object of this invention is to provide a two-way system wherein greater distances can be covered wherein the receiving circuit or necessary sensitiveness will be protected from the relatively powerful transmitting circuit and both be located comparatively near each other, and in many instances on and within the same building, which, so far as I am aware, has not heretofore been accomplished in the case of systems involving a relatively powerful transmitting circuit separate from a sensitive receiving circuit, that is to say, one having a radiating element and the other a separate collecting element for receiving. Heretofore it has been believed that the local paralysis caused by the relatively powerful sending circuit would render a sensitive receiving circuit in the same building inoperative, but I have discovered that this supposition is unfounded and am able to dispense with remote control heretofore used for medium distance communication, and also with methods heretofore proposed which balance a sensitive receiving circuit in the field of a powerful transmitter, which requires continual readjustment and consequent reduction in operating efficiency.

This invention accomplishes the following objects:

(a) Provides means whereby a complete two-way, or break-in, transmitting and receiving circuit may be made to occupy no more space and require no more equipment than a one-way transmitting and receiving

station capable of covering the same distance.

(b) Makes the improvement from a one-way to a two-way complete transmitting and receiving circuit without introducing any additional adjustments to do so.

(c) Makes the improvement from a one-way to a two-way complete transmitting and receiving circuit without reducing the customary efficiencies of either the transmitter or receiver.

In the accompanying drawings is shown a diagrammatic representation of a system embodying a preferred form of the invention, wherein

Figure 1 is a general diagram, and

Figure 2 is a detail diagram.

In carrying out the invention I provide a transmitter radiating system of high capacity and low inductance, and a receiver collecting system of low capacity and high inductance, and am thereby enabled to obtain the best conditions for simultaneous radiation and reception. The system as a whole is shown in Figure 1, wherein A represents a transmitting aerial mounted in the usual manner on masts or towers on top of the building, and also carrying a counterpoise B, the latter usually being placed below the aerial A. The aerial A and counterpoise B are wired to apparatus contained within a weatherproof box C carried by one of the masts, and the box C is connected by metal sheathed conductors F to a power unit D within the building, and the latter by suitable connections G to the receiving set E, which is placed wherever desired within the building. While only one station is shown herein, it will be understood that others similar thereto will be provided, although this is not essential since my receiver and my transmitter can be made to operate with others of different design.

The transmitting circuit CAB is supplied with power and controlled through the power unit D which is situated for convenience at the operating position near the receiving set E. The connection between C and D is by a metal sheathed or "BX" cable F having a ground connection H containing a switch I to enable grounding the sheathing at the time of installation if desirable. Inside the metal sheathing F are the three wires connecting C and D, while between D and E four wires are used.

In the specific embodiment shown herein vacuum tubes are employed, but it is to be understood that the circuit CAB may be any well-known power oscillating circuit used for transmitting, the oscillator being located in C. Where vacuum tubes are used the power unit D may include storage batteries to heat the transmitting and receiving tube filaments and to run a dynamotor which furnishes higher voltage power to the transmitter and modulator tubes. The receiving circuit may also be any one of the well-known circuits. The circuit CAB has no operating adjustments, except for wave-length, which is seldom altered, the control of the station for either telephony or telegraphy being from the position of E.

Referring to Figure 2, 1 and 2 are inductances coupling the grid and plate circuits of the transmitting oscillator 5, producing oscillations in the resonant circuit AB¹. 3 is a grid leak and condenser to maintain the grid at proper value of negative potential from the filament so as to obtain maximum tube efficiency, while 4 is a condenser to pass radio frequency but preventing the high voltage between the plate and the filament from short-circuiting through coil 1. 6 are radio frequency chokes to prevent transmitter radio frequency current from leaving or going below C, thus localizing all transmitter radio frequency at CAB. By grounding the metallic sheathing F it will now be seen that any leak of transmitter radio frequency beyond chokes 6 passes to ground through switch I and wire H by reason of the capacity between the conductors inside the sheathing F and the sheathing itself. Two of these conductors carry the heating current for the filament, and one of these and the third supply high voltage power from the dynamotor 8 between the filament and plate of oscillator 5.

The power unit D may consist of a box with parts arranged for compactness and convenience in charging, adjustment, etc., and contains storage battery 12 to heat the filament of power oscillator 5, the filament of power modulator 9, and runs the dynamotor 8. 11 is a sending telegraph relay controlled from E, and it will be seen that when relay 11 is closed the negative pole of the high voltage source 8 is connected to the filaments of tubes 5 and 9, while the positive pole of the high voltage source is connected first through the voice-frequency choke coil 7 and then to the plates of tubes 5 and 9. The choke 7 causes the total current to both tubes to be constant at voice frequency, so that if the current in modulator 9 is suddenly decreased the current in oscillator 5 is increased, and vice versa. The tube 9 is voice controlled by a telephone transmitter 16 connected in series with a battery 14 and the primary of modulation transformer 10,

the secondary being connected between the grid and the filament of the power modulator. The battery 14 heats the filaments of detector tube 19 and amplifier tube 20 located in E, and also supplies current for telephone transmitter 16, the telegraph relay 11, and break-in and key click eliminator relay 17.

Reception is by loop 18, detector tube 19, and audio frequency amplifier tube 20. 23 is an audio frequency transformer adapting the plate or output circuit of detector 19 to the grid or input circuit of the amplifier 20. Condenser 25 is provided to pass only radio frequency current around the relatively high impedance primary of transformer 23. The resonant receiving circuit includes inductance of loop 18 and variable tuning capacity 21, and is made to oscillate or nearly oscillate by variable feed-back inductance 22.

The relay 17 is provided with an additional third contact 30, so designed and connected that when key 28 is closed contacts 29 and 30 make before 30 and 31; while in opening key 28 contact 30 leaves contact 31 before contact 29 leaves contact 30. This can be effected by making the resiliency of 30 slightly greater than that of 29, 30 being non-magnetic. Since the telephone receivers 27 are in series with contacts 30, 31 and secondary of key click eliminator transformer 24, reception is only possible when key 28 is closed. Transmission of telegraphic signals is by key 28, which closes contacts 29 and 30, in series with storage battery 14 and the coil of signal relay 11, the contacts of the latter making and breaking the negative lead from the high voltage power supply. Transmission as well as reception is possible only when key 28 is closed, or its side lever closed, where the operator does not desire to manually hold the key down, thus affording break-in telegraphy. By this is meant a duplex system of telegraphic communication wherein during the communication both the sending and the receiving keys are closed, thereby producing a beat note at each station only when both keys are closed, and the opening of either key destroying the signal beat note at both stations, assuming that the local receiver and incoming oscillations are so tuned as to produce a beat note. With the receiving set tuned to the incoming signal, a sending operator hears his own sending just as a wire operator using a sounder does, and opening of the key by the receiving operator destroys the beat note at both stations to effect a break.

By providing transformer 24, and connecting receivers 27 across the secondary of transformer 24 with contacts 30, 31 in series, key click is eliminated, as would not be the case if the receivers were directly in series with plate battery 26, because they would then carry direct current from battery 26 and

a sharp annoying click would be heard in the receivers whenever this battery circuit is opened. The transformer 24 removes direct current from the receivers, but efficiently 5 passes the audio frequency signal current, thus entirely removing key click from this source. Another source of key click would be the use of a simple relay in place of the special key click eliminator relay 17, since 10 an ordinary relay upon an opening would produce a key click due to the make and break of the high voltage contacts. By the use of the third contact 30 and the arrangement for opening and closing the contacts 15 29, 30, 31 successively, click from this source is eliminated, because the telephone receivers are disconnected from the circuit at the instant of either making or breaking the high voltage supply at signal relay 11. The direct current passing through key 28 is kept as low as possible, and suitable condensers 20 are shunted across the key 28 and signal contacts at 11.

While relay armature of 17 is herein shown as actuated by the coil controlled by key 28, it is to be understood that I do not restrict myself to such arrangement, as it is obvious that 29, 30, 31 can be directly manually actuated with the elimination of key 28 25 and the relay coil, if desired.

For telephoning, the key 28 at each station is closed.

In the system as above described local paralysis is eliminated, thus permitting both 30 the sending and receiving sets to be in the same building, one being above the other, and also to operate with very high efficiencies.

The use of a closed loop for receiving and an open antenna for transmitting permits 35 the receiving and sending elements to be brought nearer each other because of the reduction in both electrostatic and magnetic coupling between the two elements. It is found in the arrangement of Figures 1 and 40 2, wherein a counterpoise is used in connection with an elevated aerial for sending and a loop for receiving below the counterpoise that the effect of magnetic coupling is negligible at the powers now in use and that making 45 the effect of accidental capacity coupling to the loop zero obviates local paralysis. I prefer the use of a small loop and to increase the receiving sensitiveness to the desired 50 value by one or possibly more stages of audio frequency amplification. Radio frequency amplifiers are not desirable as they would tend to increase any accidental transmitter 55 radio frequency in the loop circuit and thus cause local paralysis. By using a counterpoise, the parts carrying transmitter radio frequency are between the aerial and the counterpoise at C, thus localizing the entire 60 transmitting circuit so that it can be installed on the roof of a building. With this done 65 it is found that the receiving loop set, with

amplifier, equivalent in receiving sensitiveness to the antenna, although in the same building below the counterpoise, is operationally free from local paralysis, thus bringing the transmitting and receiving circuits 70 physically closer to each other than has heretofore been considered possible but still electrically isolated from each other.

The choke coils 6 are important in assisting in the isolation of transmitter radio frequency current at C, but any leakage past these chokes is grounded by reason of the large capacity between the cables and the metal sheathing. The use of the sheathing also permits placing the receiving loop near 75 F, if desired, on account of space limitations. It will be understood that the grounding of sheathing F is precautionary, as this is unnecessary if the chokes 6 function completely; in fact, under some circumstances, it is 80 even found undesirable to ground it. For the metallic sheathing F could be substituted a condenser from each of the conductors to the ground, but this would not give the shielding effect of the armor such as F necessary 85 to permit the receiving loop to be brought near the cables, whereas with F the receiving loop 18 can be as near as is desired.

It will be understood that the storage batteries, dynamotors, etc., could be replaced by a single generator designed to furnish the entire set with power. The storage batteries are placed together in D to facilitate charging, and the discharge rate from both batteries 90 12 and 14 is made equal by proper circuit design. It is found desirable to eliminate low frequency induction noises from the dynamotor by enclosing it in a metallic casing. For removing commutator 95 ripple from the dynamotor suitable means are now known.

In installation, capacity coupling between the receiving loop and transmitter via "ground", such as gas and water pipe, etc., 100 must be reduced to a minimum, either by keeping the loop a sufficient distance from such objects or else by so designing the loop oscillating circuit that the capacity effect to ground is equal from both terminals of the 105 loop, thus preventing transmitter radio frequency coming in via "ground" to the loop, thence entering the detector tube circuit and causing local paralysis. As herein shown, this object is accomplished by the adjustment of condenser 33 at the time of installation, together with the proper "polarity" of 110 loop terminals 32. In using the receiving circuit in Figure 2 with condenser 33, if a grounded metallic object is closer to one side 115 of the loop than the other and there is some local paralysis in the receiving set by a capacity coupling between the said object and the loop, reversing the loop terminals at 32 120 with condenser 33 disconnected will either 125 130

increase or decrease the capacity coupling. Consequently, one of the two possible ways to connect the loop at 32 will permit some value of condenser 33, when reconnected, to 5 balance the transmitter radio frequency which may accidentally stray to the receiving loop, either through the air from the said object or by leakage along the conductors joining C, D and E.

10 Choke coils may also be inserted in the conductors joining D and E, at say position 15, to supplement the chokes at 6 in C. It has been found that when F is not grounded and poor chokes are employed at 6, there is 15 leakage of transmitter radio frequency current to D, and thence by capacity coupling between the sending and receiving apparatus over D, and finally to the loop receiving circuit. In such a case would the chokes at 15 20 be of particular assistance. Chokes might also be inserted in the four wires, as indicated at 34, for the same purpose, but in present instruments chokes at 15 and 34 have not been found necessary.

25 To tell if the radio frequency receiving loop circuit is free from local paralysis, for given combination of transmitter and receiver wave-lengths, stop the transmitter from radiating and adjust the loop circuit 30 to an oscillating state, and find some point to touch with a wet finger which will give a click in the head receivers. Then adjust the receiving circuit so as not to oscillate; no click will then be heard. Now if the 35 transmitter is permitted to radiate again, and no click is heard while touching the loop with finger as before, the receiving circuit is free of local paralysis for all practical purposes, whereas if a click is now heard the receiver is being affected (forced to oscillate) 40 by the transmitter, either by transmitter radio frequency current leaking through improperly choked connecting conductors, or by electrostatic or magnetic induction. A 45 much simpler way to tell whether or not there is local paralysis for a particular combination of sending and receiving wave-lengths, etc., at each station, and the method used in making installations, is to set sender 50 and receiver to desired wave-lengths and listen to the distant station's signal with and without the local sender radiating. If there is no difference in the intensity or quality of the incoming signal when sender is radiating 55 and when it is not, then for all practical purposes the receiver is free of local paralysis. It is thought that electrostatic induction to the receiving loop has nearly always predominated over magnetic coupling to cause local 60 paralysis, except where the transmitter capacity is between aerial and ground (instead of between aerial and counterpoise), and the receiving loop is placed off to one side instead of underneath, as may be preferable 65 for high power transmitters.

If the loop is two or three floors below the aerial-counterpoise system, there does not seem to be any magnetic coupling whatever, even when the transmitter power is increased considerably. What coupling there is from the transmitter causing local paralysis can invariably be eliminated by obtaining the right value of condenser 33 and "polarity" of loop 32 in Figure 2. If it is desired to operate the receiver and transmitter at a station on substantially the same wave-length, say almost near enough to produce an audible beat note, if the receiving set is oscillating, it may be found necessary to also position the receiving loop 18 relatively to the rest of the apparatus. This is especially true if large transmitter power or a large receiving loop is utilized. These three installation adjustments also provide excellent means of adjusting the intensity 80 of "side tone" at the time of installation.

In this system an efficient transmitting circuit is localized between antenna and counterpoise on a roof; then below and in the same building receiving is confined to an 90 efficient loop circuit. The arrangement of 32 and 33 in Figure 2 at the receiving loop, therefore, simply balances the overflow, or what transmitter radio frequency current may accidentally get away from the transmitter and be induced in the receiving circuit as by capacity coupling via gas and water pipes, etc. It is interesting to note that if condenser 33, Figure 2, is large enough, it is the equivalent of grounding 95 the filament of the receiving set, which is desirable in that it protects the receiver local frequency from changes due to operator touching exposed parts of the circuit having filament potential.

By radio frequency chokes, as at 6, Figure 2, is meant any unit or combination which might be connected to or inserted at a point to prevent radio frequency current 100 from passing.

The receiver will be preferably operated on a slightly different wave-length than the transmitter, because in telegraphy the beat note caused by the local transmitter would "jam" the distant signal, and for telephony there would be too loud a "side tone," or possibly "howling" such as occurs in wire telephones when receiver and transmitter are brought together. In telephony, the receiver will preferably be adjusted not to oscillate, but "tickled up" by feed-back 110. For telegraphy, the effect of 22 will be made such as to make receiving loop oscillate in the usual manner for continuous wave reception.

What I claim is:

1. In a radio communication system, a station comprising an elevated radiating element including an aerial and a counterpoise the ratio of whose effective capacity to in- 130

- ductance is relatively high, a receiving element below the radiating element whose ratio of effective capacity to inductance is relatively low, means for supplying power, 5 and sending and receiving means.
2. In a station for simultaneous duplex radio communication, a radiating system having relatively high capacity and low inductance and a separated receiving system 10 in the same building having low capacity and high inductance operating on different frequencies, means for shielding said receiving system from the field of said radiating system, and means for selectively operating the radiating system to transmit telegraphically or telephonically.
3. In a radio communication system, a station comprising an elevated radiating element, a counterpoise below the radiating 15 element, a receiving element below the counterpoise, and sending and receiving means.
4. In a radio communication system, a station comprising an elevated radiating element, a counterpoise below the radiating 20 element, a loop receiving element below the counterpoise, and sending and receiving means.
5. In a radio communication system, a station comprising an elevated radiating element, a counterpoise below the radiating 25 element, means for supplying power to the radiating element, means for localizing sending radio frequency in the radiating element counterpoise circuit, a receiving element below the counterpoise, sending means 30 controlling the radiated power and receiving means controlling the received power, both located adjacent the receiving element.
6. A radio communication system including a radiating aerial, a counterpoise cooperating with said aerial and forming therewith a radiating system, a sending means connected to said radiating aerial and counterpoise, and a receiving means having 35 its receiving aerial located near the radiating system and in the zone shielded by the counterpoise.
7. A radio system arranged for duplex communication including a radiating aerial, 40 a counterpoise cooperating with said aerial and forming therewith a radiating system, a sending means connected to said radiating aerial and counterpoise, a receiving means having its receiving aerial located near the radiating 45 system and in the zone shielded by the counterpoise, a source of power for the sending and receiving means, and means for preventing the transfer of radio frequency energy from the sending means to the source 50 of power.
8. A radio communication system including a radiating element having sending means cooperating therewith, a receiving loop having receiving means cooperating 55 therewith, a single source of power for said sending and receiving means, and means for equalizing the capacity effect to ground in the loop oscillating circuit, including a grounded condenser connected to one of the loop terminals whereby to prevent local 60 paralysis in the receiving means by capacity coupling between the loop and adjacent metallic objects.
9. A radio communication system embodying an elevated antenna and counterpoise, an elevated oscillating element adjacent the antenna and counterpoise, a receiving station comprising a loop and an oscillatable element at such distance from the counterpoise as to be substantially out of the sending field, sending and receiving controlling 65 means adjacent each other and the loop, a power unit conveniently near the receiving station and connected to both the receiving loop and the sending oscillator, and means 70 for preventing local paralysis of the receiving system.
10. A radio communication system embodying an elevated antenna and counterpoise, an elevated oscillating element adjacent the antenna and counterpoise, a receiving station comprising a loop and an oscillatable element at such distance from the counterpoise as to be substantially out of the sending field, sending and receiving controlling 75 means adjacent each other and the loop, a power unit conveniently near the receiving station and connected to both the receiving loop and the sending oscillator, and means 80 for preventing local paralysis of the receiving system.
11. In a station for duplex radio communication, a transmitting radiating element, signaling means controlling the radiations thereof, a receiving loop having one side connected to detecting means, detecting means located adjacent said signaling means, and a condenser between the other side of the loop and ground proportioned to eliminate electrostatic coupling in the loop circuit due to objects within the 85 field of said radiating element.
12. In a station for duplex radio communication, an open antenna radiating structure supported on a building, a unit for supplying oscillations thereto whose power 90 supply and control come via metal covered conductors from within the building, a loop receiving set situated within said building and receiving on a different frequency from that of the transmitter, means for preventing transmitter energy from passing through 95 said conductors to the receiving circuit, and means for preventing transmitter energy 100.

from passing to the receiving circuit by electrostatic coupling with objects within the field of said antenna.

13. In a two-way radio communication system, an aerial and a counterpoise supported between elevated masts, an oscillating sending element connected thereto mounted on a mast, a power supply connected thereto by cables containing radio frequency choking means, a sheathing for said cables, and means for controlling the radiated oscillations to transmit intelligence.

14. In a duplex radio communicating system including a transmitting circuit, a radiating element, and a loop receiving circuit, a source of power supply connected to the transmitting and receiving circuits, and means for establishing a capacity coupling between the loop circuit and a ground whereby to secure a proper balance of the loop circuit.

15. In a duplex radio communicating system having a transmitting circuit operatively connected to a radiating antenna and a counterpoise, a receiving circuit operatively connected to a loop antenna, and a common source of power supply operatively connected to both of said circuits, a method of operating said system without paralyzing the receiving circuit by local transmitter energy which consists in preventing the transmission of radiated energy from the transmitting circuit to said receiving circuit, and balancing out radiated energy in said loop caused by electrostatic coupling with adjacent metallic objects.

16. A duplex radio communication system comprising a power oscillating circuit including an aerial, a counterpoise and an oscillator, the oscillator being enclosed in a weatherproof box; a receiving circuit including a coil aerial, and detecting and amplifying means, said means being enclosed in a metallic shield; a power unit including means for supplying electrical energy to the

oscillating and receiving circuits, said unit being enclosed in a metallic shield, and conductors connecting the power unit with the respective circuits, at least some of said conductors being enclosed in grounded metallic shields.

17. In a simultaneous duplex continuous wave radio telegraph system having cut-in, controlled by a transmitting key, with heterodyne reception through telephones, a transformer between the audio frequency circuit and the telephones, the latter being in the transformer secondary circuit, and switching means comprising successively operated contacts controlled by the key for eliminating key click in the telephones.

18. A two-way radio telegraph system comprising at each of two stations a sending antenna and a receiving loop, and a key with means whereby a local signal beat note is audible at each station when both keys are closed, means whereby opening of a key at one station effects a variation of the signal beat notes to effect a cut-in, and means controlled by the cutting in key to eliminate key click in the beat note receivers.

19. In a station for duplex radio communication, a transmitting radiating element and a vacuum tube oscillating circuit connected thereto, the said oscillating circuit receiving its filament and plate power supply from a distant generator, means for removing generator ripple in the plate power supply, a receiving system comprising a closed loop receiving element having detecting and amplifying means connected thereto, means for selectively operating the oscillating circuit to transmit telegraphic or telephonic radiations, and control means for the receiving circuit actuated by said operating means.

Signed at New York city, in the county of New York and State of New York, this third day of September, A. D. 1920.

PAUL WARE.
